UNITED STATES PATENT OFFICE.

OTTO MACKENSEN, OF JENA, GERMANY, ASSIGNOR TO THE FIRM OF CARL ZEISS, OF JENA, GERMANY.

DOUBLE TELESCOPE.

1,067,532.

Specification of Letters Patent.

Patented July 15, 1913.

Application filed July 31, 1912. Serial No. 712,387.

To all whom it may concern:

Be it known that I, Otto MACKENSEN, a citizen of the German Empire, residing at Jena, Germany, have invented a new and useful Double Telescope, of which the following is a specification.

The invention relates to double telescopes, more particularly to hand-telescopes (field-glasses, opera-glasses), in which the oculars 10 are connected together by means of a coupling, usually in the form of a bridge, so that they may be unitedly focused. For actuating this focusing mechanism a screw has been used up to the present, which was 15 journaled in a female thread between the single telescopes and the free end of which rotated as a journal in the coupling-bridge. The screw either was given an inconveniently large diameter and became correspondingly heavy or it wore rapidly. In 20 either case the actuating disk of the screw increased the size and weight of the instrument.

These drawbacks may be avoided according 25 to the invention by journaling the actuating means for the united focusing to the socket of one of the two oculars coaxially. With this arrangement a saving in weight and space is directly combined, because the 30 sockets of the oculars already have approximately the circumference that is requisite for the actuating ring. The displacement of the ocular guided on the same ocular-socket, brought about by such an actuating ring, is 35 again transmitted by means of the coupling-bridge to the other ocular. A special advantage is gained in the case of the larger sizes of double telescopes, where up to now it entailed an effort to reach the actuating disk, 40 as the hand had at the same time to span one of the single telescopes.

The simplest way of carrying out the invention is to let one ocular itself serve as the actuating means by journaling it to its 45 socket by means of a screw-thread.

In order to insure the transmission of the motion of one ocular through the coupling-bridge to the other ocular, it is advisable to connect the middle part of the coupling-bridge in the direction parallel to the oculars by means of a guiding member with the double telescope proper. When the double telescope has a joint between the single telescopes and a corresponding joint in the coupling-bridge, the guiding member will ap-

propriately be disposed coaxially to the joints. The customary arrangement for compensating, by focusing one of the two oculars, any difference in the refractive condition of the two eyes, is best fitted to that 60 ocular, to which the actuating means for the united focusing does not belong.

In the annexed drawing a constructional example of the invention is shown.

The right-hand ocular *a* forms the actuating means for the united focusing and is for this purpose journaled in the interior of its ocular-socket *b* by means of a screw-thread. The two single telescopes *c* and *d* are connected by means of a joint *c*^o, *d*^o. 70 Similarly the coupling-bridge consists of two members *e* and *f*, which are connected by means of a joint. To the member *e* a rod *e*^o is fixed, which is guided in the hollow joint-journal *c*^o. The right-hand bridge-member *f* is rotatably journaled on the ocular *a*. The left-hand bridge-member *e* carries a sleeve *e*¹, which is guided on the left-hand ocular-socket *g* and on which the ocular *h* appertaining to this socket is journaled 75 by means of a thread, which serves for the said separate focusing.

I claim:

1. In a double telescope two single telescopes connected together, an ocular in each 85 telescope, guided in its axial direction, a coupling-bridge between the said oculars for the united focusing of the latter, and actuating means for such focusing, journaled coaxially to one of the ocular sockets. 90

2. In a double telescope two single telescopes connected together, an ocular in each telescope, guided in its axial direction, a coupling-bridge between the said oculars for the united focusing of the latter and actuating means for such focusing, this means being one of the oculars itself, which ocular is journaled to its socket by means of a screw-thread. 95

3. In a double telescope two single telescopes connected together, an ocular in each telescope, guided in its axial direction, a coupling-bridge between the said oculars for the united focusing of the latter, a guiding member adapted to guide the oculars conointly, which member connects the said coupling-bridge and the double telescope proper and is directed parallel to the oculars, and actuating means for the said focusing, this means being one of the oculars 100

105

110

itself, which ocular is journaled to its socket by means of a screw-thread.

4. In a double telescope two single telescopes, an ocular in each telescope, a joint connecting the two telescopes, a coupling-bridge between the said oculars for the united focusing of the latter, having a corresponding joint, a guiding member adapted to guide the oculars conjointly, which member connects the said coupling-bridge and the double telescope proper, is directed parallel to the oculars and disposed coaxially to the joints, actuating means for the said focusing, this means being one of the oculars itself, which ocular is journaled to its socket by means of a screw-thread.

5. In a double telescope two single telescopes, an ocular in each telescope, a joint connecting the two telescopes, a coupling-

bridge between the said oculars for the 20 united focusing of the latter, having a corresponding joint, a guiding member adapted to guide the oculars conjointly, which member connects the said coupling-bridge and the double telescope proper, is directed parallel to the oculars and disposed coaxially to the joints, actuating means for the said focusing, this means being one of the oculars 25 itself, which ocular is journaled to its socket by means of a screw-thread, and means 30 adapted for independently focusing the other ocular relatively to the coupling-bridge.

OTTO MACKENSEN.
